UNITED STATES PATENT OFFICE.

ERNEST YEOMAN ROBINSON, OF WITHTINGTON, MANCHESTER, ENGLAND, ASSIGNOR
TO METROPOLITAN-VICKERS ELECTRICAL COMPANY LIMITED, OF LONDON, ENGLAND, A BRITISH JOINT STOCK COMPANY.

ELECTRIC TUBE DEVICE HAVING COILED FILAMENTS.

Application filed May 24, 1924, Serial No. 715,655, and in Great Britain June 12, 1923.

This invention relates to electric tube devices of the kind having coiled filaments or coiled wire cathodes such as electric incandescent lamps, electron discharge tubes, and like devices. The object of the invention is an improved method of supporting such coiled members.

A common method of supporting a helical filament or cathode consists in bending the filament wire at the end convolution substantially at right angles thereto so that the wire lies in an extension of a generating line of the cylinder containing the helix and the end portion of the wire thus conformed is secured to a rigid support such as lead-in wires. Another method commonly adopted is to reduce progressively the diameter of several of the end turns of the helix so as to form a conical spiral and to bend the 20 end of the filament wire so that it is co-axial with the helix. In the first case the end turns of the helix tend to pull out, that is to say, the pitch of the helix is not uniform and further the helix can rotate about the 25 point of support since the latter is not co-axial with the helix. In either case the filament is not rigidly supported and it is found that the axis of the whole helix is shifted out of its normal position when the filament 30 is heated this being probably due to unequal heating of the bent end portions of the filament which are attached to the supports or lead-in wires.

Furthermore when a filament cathode is employed in a vacuum electric tube in which the gap between the cathode and another electrode such as the anode, is small, as described in the specification of my copending application Serial No. 603,715, filed 27th 40 November 1922, it is important that the filament should not move over and touch the other electrode. It is also important that the cathode should be rigid in itself, that is, the cathode should not be capable of being 45 pulled over to the anode by electrostatic strain existing in the vacuum electric tube. Moreover, it is important in the construction of short gap valves that the cathode should be accurately registered with respect to the 50 support or supporting stem in order that the electrodes may be easily assembled by the use of jigs.

According to the present invention the

end convolution of a helical filament or cathode is supported at a plurality of points 55 around said convolution so that a rigid mounting of the filament is obtained and considerable rigidity is imparted to the filament as a whole, whereby the above mentioned defects are removed or considerably 60 reduced. The several supports are preferably connected electrically in parallel. Alternatively the support may be attached to a convolution other than the end convolution. The end convolution of the filament 65 may be supported continuously over a relatively large portion of its length, for example, over a portion which is at least equal in length to half of the perimeter of the convolution. Several of the end convolutions 70 may be supported continuously in this manner.

To enable the invention to be clearly understood it will now be described with reference to the accompanying drawings in 75 which Fig. 1 is a perspective view of part of a coil filament supported in accordance with the invention, Fig. 2 a view of modified form of supporting member and Fig. 3 a perspective view of another form of the supporting member. Fig. 4 is a sectional view 80 of part of a coil filament supported by means of a still further form of supporting member. Fig. 5 is an elevation partly in section of the electrodes of a vacuum electric rectifier having a coiled filament supported in 85 accordance with the invention, Fig. 6 is a side view of the arrangement illustrated in Fig. 5 and Figs. 7 and 8 are views of details. Fig. 9 is an elevation of modified electrodes 90 of a vacuum electric rectifier. Fig. 10 is a sectional elevation of a still further construction of the electrodes of a vacuum electric tube, and Figs. 11 to 15 inclusive are plan views of certain members of the structure shown in Fig. 10.

Referring to Fig. 1 of the drawings, the end portion of a helically coiled filament constituting an electrode of an electric tube device is indicated at 1, and a supporting member for such end of the coiled member is indicated at 2, the member 2 being attached to a supporting stem 3 which may constitute a lead-in wire for the electrode. The member 2 is provided with a plurality 100 of radial arms 4, for example three arms as

illustrated, said arms having a symmetrical angular displacement. The ends of the arms 4 are severally bent round the end convolution of the coil filament 1 as indicated at 5 so as firmly to clamp the latter. The supporting member 2 may be made of sheet metal of sufficient thickness to provide the required rigidity.

When the filament 1 is of tungsten or 10 molybdenum the support 2 and the lead-in conductor or stem 3 may conveniently consist of molybdenum or alternatively of nickel if the support and stem have sufficient mass. The end turn of the filament 1 may be 15 twisted slightly so that it lies in a plane at right angles to the axis of the helix. The three-armed support 2 may be riveted, welded or otherwise secured to the stem or lead-in wire. By the use of an additional 20 washer of molybdenum, for example riveted to the stem, thinner material may be employed for constructing the three-armed support owing to the further support provided by the washer and also the bending of the 25 arms of the support around the convolutions of the filament wire is facilitated. As illustrated in Fig. 2, the three-armed support may be in the form of a triangular plate the corners of which may be bent around the end 30 convolution of the filament wire. The triangular plate may be of relatively thin sheet metal supported by a washer 2^a attached for example by riveting or welding to the end of the stem 3.

35 A modified form of support illustrated in Fig. 3, comprises a plurality of strips 6, say three, of nickel or molybdenum which are attached to a supporting stem 3 and are conically splayed, their free ends being bent as 40 at 5 around the end convolution of the wire as previously described with reference to Fig. 1.

A further form of support as shown in Fig. 4 comprises a short tube of diameter 45 which is equal to or slightly larger than the internal diameter of the filament helix 1 and said tube is provided with a flange or flare 8 and one or more of the end convolutions of the helix are disposed on the supporting 50 tube and retained thereon by means of the flare or flange a portion of the circumference of which may be interrupted to permit a turn of the helix to pass through it. The flange is preferably provided with projecting 55 tongues which may be bent over one or more turns of the helix to grip the same. The end convolutions thus supported may be arranged as shown to have a smaller pitch than the main portion of the helix or may 60 even be arranged so that they are substantially in contact with one another. The tube 7 is attached to the stem 3 in any desired manner.

Referring to Figs. 5 to 8 inclusive, the elec- 45 trodes therein illustrated are as set forth in

the specification above referred to, that is to say, the cathode 1 is of such a form as to provide a concentrated source of electrons, the anode 9 is closely spaced from the cathode 1 so that in combination with the concentrated electron source the inter-electrode space is small and the thermionic discharge between the cathode and anode is confined to such small inter-electrode space and thus the paths available for the discharge are a 1 70 short. The cathode 1 consists of a helix of suitable material such as tungsten, or it may for example be of molybdenum coated with a mixture of barium and strontium oxides to facilitate the emission of electrons therefrom. The convolutions of the helix are closely spaced from one another in order to provide the concentrated source of electrons. 80

The cathode helix is supported at its ends by the molybdenum or nickel stems 3 to 85 which are attached molybdenum or nickel washers 10 which in turn support relatively thin molybdenum or nickel supporting members 2 having arms which are bent around one or more of the end convolutions of the 90 helix. Such construction will be clear from Fig. 8 which is drawn to a larger scale than Figs. 5 and 6. The stems 3 are supported in the tubes in the manner hereinafter described. 95

The anode 9 is constructed of two similar sheet metal plates bent to the shape shown in Fig. 7, and superimposed to one another so as to constitute a tube within which the cathode 1 is disposed. In addition two relatively small tubes 11 are provided in the flange portion 12 of the anode thus constituted, and the supporting wires 13 of nickel or molybdenum for the anode pass into the tubes 11. The two portions of the 105 anode 9 are welded, stapled or otherwise fixed together and to the supports 13. The lower ends of the supports 13 are fused into the glass pinch 14 at the end of the re-entrant tube 15 of the device. The supports 110 13 may be constructed of two materials, the portions in the neighbourhood of the anode being of molybdenum and the portions which pass into the pinch 14 being of nickel. One of the supports 13 passes through the 115 seal 14 to an external lead-in conductor 16.

The lower of the filament supports 3 is welded to a filament lead-in wire 17 which passes through the pinch 14 to an external conductor 18 whilst the upper filament support 3 is welded between a pair of tongues 19 at the end of a nickel bracket 20 which is fused as indicated at 21 into the pinch 14. The cross section of the nickel bracket 20 may be angular or channel to provide 120 stiffness. The bracket 20 is connected through the seal 14 to an external conductor 22.

Referring to Fig. 9 the construction 130 therein illustrated only differs from that

illustrated in Figs. 5 and 6 in that the supporting stems 13 for the anode 9 extend beyond the upper end of the latter and are connected together at both ends by means of 5 cross members 23 of pyrex glass into which the stems 13 are fused. The latter may conveniently be of molybdenum which material has a coefficient of expansion of the same order as that of pyrex glass. The members 10 13 and 23 constitute a rectangular framework which enables the electrodes to be permanently fixed and registered with respect to one another in an easy manner similar to that described and claimed in the specification 15 of my copending application Serial No. 722,811 filed June 27, 1924. The filament supporting stems 3, preferably of molybdenum, are also pinched into the cross members 23. In assembling the electrodes they 20 are held and registered with respect to one another in a jig whilst the cross members 23 are being pinched on to the stems and supports. The upper filament support 3 is connected with a member 24 which is connected 25 with an external filament lead.

Referring now to Figs. 10 to 15, the cathode 25 is a molybdenum tube which is coated on its outer surface with a mixture of barium and strontium oxides. The coating 30 may be effected in the manner described in the specification of copending application Serial No. 715,653 filed May 24, 1924. The cathode tube 25 is heated to a temperature at which it emits electrons readily by 35 means of a heating coil 26 axially disposed within the tube 25 and supported from the stems 3 in the manner hereinbefore described with reference to the helical cathode 1. The anode 9 is co-axial with the cathode 40 tube 25 and closely surrounds the latter so that the inter-electrode space is small. The discharge is confined to this small inter-electrode gap by reason of the fact that the ends of the cathode tube 25 do not become 45 sufficiently heated to emit electrons freely. To this end the cathode tube 25 is longer than both the heating coil 26 and the anode 9 in order that its ends may remain cool and constitute effective shielding means for confining the discharge.

The electrodes are supported on the framework in a manner similar to that set forth and claimed in the specification of my copending application Serial No. 722,811 above referred to. The framework comprises a 50 pair of parallel nickel wires 27 and a pair of end members 28 attached thereto, and the electrodes are mounted upon this framework by a plurality of cross members such as illustrated in Figs. 11 to 14 inclusive similar to those described and claimed in the specification of my copending application Serial No. 722,811 above referred to. One of the members 28 is shown in plan in Fig. 11. The 55 anode 9 may assume the form shown in sec-

tion in Fig. 15, comprising four sheet metal plates bent to the shape illustrated so as to constitute when assembled a tube having radial flanges 29. The anode 9 thus constituted is supported by means of a pair of 70 cross pieces 30 one of which is illustrated in plan view in Fig. 12. Each cross piece 30 comprises a diamond shaped plate having a central perforation 31 with four radial extensions 32 corresponding to the shape of 75 and adapted to receive the anode 9. The plate 30 is provided at its ends with perforations 33 through which the side members 27 of the rectangular framework pass. The plates 30 are fixed in position upon the side 80 members 27 of the framework by welding or by means of members 34 clamped or welded around the members 27 or are otherwise fixed thereon.

The cathode tube 25 is supported by cross pieces 35 one of which is separately illustrated in plan in Fig. 13. Each member 35 comprises a metal plate having a central perforation 36 adapted to receive the cathode tube 25 and end perforations 37 through 90 which insulation tubes or bushes 38 of steatite or glass are passed, the bushes 38 being disposed upon the upper and lower ends of the side members 27 of the supporting framework. They may be maintained 95 in position by means of members such as 34 as clearly shown in Fig. 10. The cathode tube 25 may be supported in the two cross-members 35 by means of outwardly bent tongues as shown provided on the ends of 100 the tube. The supporting stems 3 of the auxiliary heating coil 26 are supported from cross pieces 39 one of which is illustrated in plan in Fig. 14. It comprises a metal plate having a central perforation 40 through 105 which the stem 3 passes, and two end perforations 41 through which the insulating bushes 38 pass. The stems 3 are secured in the supporting cross pieces 39 in any convenient manner such as by welding metal on 110 either side of the cross pieces as indicated at 42, whilst the cross pieces 39 are themselves secured to the insulating bushes 38 by binding wires as indicated at 43. In addition 115 the supporting stems 3 of the auxiliary heating coil 26 are guided or registered by means of further cross pieces 44 which are similar in construction to the cross pieces 39 (see Fig. 14), and are similarly fixed to the insulating bushings 38.

The whole framework carrying the electrodes mounted thereon as described is supported from the re-entrant tube 15 of the vacuum device by means of a clamp 45 which surrounds the re-entrant tube and carries 120 two arms 46 to the upper ends of which are welded nickel clips 47 which are in turn connected by means of binding wires as indicated at 48, to the lower pair of insulating bushings 38. The upper and lower stems 3 125

of the heating coil 26 are connected respectively to lead-in conductors 49 and 50 passing through the pinch of the re-entrant tube 15. The lead-in wire 51 for the cathode 25 5 is connected with a conductor 52 which in turn is connected with one or other or both of the cross pieces 35 which support the cathode.

I claim as my invention:—

19. 1. The method of imparting rigidity to a helically coiled filamentary member of an electric tube device without short-circuiting the convolutions thereof, which consists in connecting a filament support both mechanically and electrically at a plurality of points distributed around at least one of the end convolutions of the helically coiled member at least one end thereof.
20. 2. An electrode structure for an electric tube device comprising a helically coiled filamentary member, a supporting member for supporting said filamentary member at at least one of its ends, said supporting member being secured to at least one of the end convolutions of the filamentary member at a plurality of points distributed around its periphery, and a lead-in member rigidly connected to said supporting member and extending axially from an end of said filamentary member.
21. 3. For an electric tube device having a helically coiled filamentary member supported only at its ends, a supporting member for supporting said filamentary member at at least one of its ends, said supporting member comprising a plurality of radiating electrical conducting arms which are connected both mechanically and electrically at a corresponding number of points distributed around at least one of the end convolutions of the filamentary member.
40. 4. In an electric tube device having a helically coiled filamentary member sup-

ported only at its ends and a cooperating electrode supported in closely spaced relation to its periphery, a supporting member for supporting said filamentary member at at least one of its ends, said supporting member comprising an element having a plurality of radiating arms which are secured at a corresponding number of points distributed around at least one of the end convolutions of the filamentary member.

5. In an electric tube device having a helically coiled filamentary member supported only at its ends and a cooperating electrode supported in closely spaced relation thereto, a supporting member for supporting said filamentary member at at least one end, said supporting member comprising a thin sheet metal member having a plurality of radiating arms which are secured at a corresponding number of points distributed around at least one of the end convolutions of the filamentary member, said arms being bent around said convolution, and a lead-in member for said filamentary member connected to said supporting member.

6. For a helically coiled filamentary member of an electric tube device, a support for at least one of the end convolutions thereof comprising a metal rod constituting a lead-in wire, a sheet-metal triangular member attached to the end of said rod, and a disk also attached to the end of said rod adjacent to the triangular member so as to stiffen the same, the relative dimensions of the disk and triangular member being such that the apices of the latter project beyond the disk and can be bent around an end convolution of the filamentary member.

In testimony whereof I have hereunto subscribed my name this ninth day of May, 1924.

ERNEST YEOMAN ROBINSON.
